UNITED STATES PATENT OFFICE.

JOHN N. AHRENS, OF UNION, NEW JERSEY.

SASH-LOCK.

SPECIFICATION forming part of Letters Patent No. 595,511, dated December 14, 1897.

Application filed June 9, 1897. Serial No. 639,980. (No model.)

To all whom it may concern:

Be it known that I, JOHN N. AHRENS, of the township of Union, in the county of Hudson and State of New Jersey, have invented 5 a new and Improved Sash-Lock, of which the following is a full, clear, and exact description.

This invention is a sash-fastener by means of which the sashes may be held open a certain degree and prevented from being 10 repetitiously forced farther open.

This specification is the disclosure of one form of my invention, while the claim defines the actual scope of the conception.

15 Reference is to be had to the accompanying drawings, forming a part of this specification, in which similar characters of reference indicate corresponding parts in all the figures.

Figure 1 is a front elevation of the invention, showing it in use. Fig. 2 is a side elevation thereof, and Fig. 3 is a detail section on the line III III of Fig. 2.

One or two of my sash-locks may be applied to a single window. If two are employed, one 25 is arranged at each side of the sashes. The drawings show fragments of one side of each sash and one sash-lock applied thereto.

The upper sash A and the lower sash B are arranged as usual. The sash A carries at its 30 side bar a ratchet-plate 5, which is rigidly secured thereto. Fixed to the upper side portion of the lower sash B is an angle-plate 6, on which two slightly-flexible standards 7 are cast or fixed, and working in the upper portions of the standards 7 is a thumb-screw 8, on which, between the plates 7, swings a pawl 9. By operating the thumb-screw 8 the standards 7 may be moved toward and from each other, so as to clamp the pawl 9 and hold it 35 rigidly in a certain position. Pivoted between the standards 7 at their lower portions is a link 10, which has an angular lower end engaged by a leaf-spring 11. The spring 11 serves to hold the link 10 securely in the position shown in the drawings or raised approximately perpendicular alongside of the

standards 7. The free end of the link 10 carries a ratchet-shoe 12, coacting with the plate 5, and the free portion of the link 10 has a notch 13 coacting with the free end of the 50 pawl 9.

The drawings show the sashes in closed position where the parts 5 and 12 are interlocked. This will effectually prevent the sashes being opened without disengaging the 55 shoe 12 and the plate 5. If it be desired to open the window a slight degree, the shoe 12 is disengaged from the plate 5 and the sashes moved, after which the shoe is reengaged, and it will now be impossible to move the 60 sashes farther to an open position without disengaging the locking parts. The screw 8 may be tightened to hold the pawl 9 firmly engaged with the recess 13 of the link 10, whereupon no shaking or rattling of the 65 sashes will dislodge the pawl.

Various changes in the form, proportion, and minor details of my invention may be resorted to without departing from the spirit and scope thereof. Hence I do not consider 70 myself limited to the precise construction herein shown, but believe that I am entitled to all such variations as come within the terms of my claim.

Having thus described my invention, I 75 claim as new and desire to secure by Letters Patent—

The combination of a base-plate, two yielding standards mounted thereon, a screw passed through the standards, a pawl pivoted 80 on the screw between the standards and capable of being clamped friction-tight between the standards by the action of the screw, a link pivoted between the lower portions of the standards, a leaf-spring held on the base-plate and pressing the link, the link being 85 engaged at its free portions by the pawl, and a shoe carried by the link.

JOHN N. AHRENS.
